CRANKCASE CONSTRUCTION

John J. Wharam, Dearborn, and Paul C. Bastien,
 Grosse Pointe, Mich., assignors to Ford Motor
 Company, Dearborn, Mich., a corporation of
 Delaware

Application January 14, 1944, Serial No. 518,215

7 Claims. (Cl. 184—6)

1

This invention relates to the construction of internal-combustion engine crankcases; and, more particularly, to a crankcase or oil pan having a wet sump divided into a plurality of separate compartments.

The object of this invention is to devise a wet sump crankcase in which provision is made to insure an adequate supply of oil to the oil pump even though the engine is operating at a considerable angle of inclination. Particularly in ordnance equipment, such as tanks and armored cars, the conditions of use are such that a vehicle may be called upon to operate for a considerable period of time at angles up to 30° to the horizontal. In ordinary crankcase constructions this necessarily results in a concentration of oil at the low end of the oil pan (which may be in the front or back of the engine, depending upon the sense of the inclination). Thus, it is not possible to locate a single oil intake in a position in which it will always be immersed in oil. The inevitable result is that the oil pump under certain extreme conditions will run dry; the engine bearings will not be supplied with necessary oil, and engine failure will be accelerated.

The advantage of the present construction is that by a few simple modifications, a conventional crankcase or oil pan may be so changed that a supply of oil is available to the oil intake and oil pump and to the lubricating system of the engine under all operating conditions. Another advantage is that the operation of the device is entirely automatic and not affected by the direction of the inclination—that is, whether the engine is pointing upwardly or downwardly—but under all these circumstances will insure the supply of an adequate quantity of oil to the oil pump. Yet another advantage is that the device which realizes these benefits is a compact unit which can be accommodated directly on the engine crankcase, so that a minimum of change is required and which is as dependable in action as the conventional pumps heretofore used. A further advantage is that the construction devised strengthens the crankcase construction itself. Still another advantage is that the specific construction may be so arranged, that for purpose of service or draining of the oil pan, it can be treated the same as a conventional construction. While the construction shown may be designed to operate under almost any angle of inclination, the limiting factor is found in the angle at which the tractive effect of the vehicle's wheels or tracks decreases, which—for practical purposes—may be taken as 30°.

2

With these and other objects in view, the invention consists in the arrangement, construction, and combination of the various parts of the improved device as described in the specification, claimed in the claims and illustrated in the accompanying drawings, in which:

Figure 1 is a plan view of the crankcase of this invention.

Figure 2 is a vertical longitudinal section taken on the line 2—2 of Figure 1.

Figure 3 is a vertical transverse section taken on the line 3—3 of Figure 1.

Figure 4 is a partial plan view of an end portion of the crankcase showing the arrangement of the overflow pipe taken substantially as indicated by the line 4—4 of Figure 5.

Figure 5 is a vertical longitudinal section corresponding to the portion of the crankcase shown in Figure 4.

Figure 6 is a vertical transverse section taken on the line 6—6 in Figure 4 and showing the drain plug construction.

Figures 7, 8 and 9 are diagrammatic views showing the operation of the crankcase when the vehicle is level, inclined forwardly and inclined rearwardly, respectively.

Referring to Figures 1 and 2, 10 indicates, generally, a crankcase casting having a sump 11 and flanges 12 by means of which it may be attached in the usual manner below an engine block. An example of the type of engine to which this crankcase has been adapted is shown in copending application Serial No. 439,632, filed April 20, 1942, now Patent No. 2,349,157. This is an eight-cylinder V-type—the center lines of the cylinders being shown by the dotted lines 13, and the center lines of the bearings are indicated by the dotted lines 14. This will indicate the relative orientation of the particular crankcase and engine. The sump 11 is divided by a transverse wall 15 into a front chamber 16 and a rear chamber 17, although the designation as front and rear is only relative as construction is equally applicable in the reverse arrangement. A front engine pan 18 extends over the front chamber 16 and the transverse wall 15 underneath the engine block so that oil from the front four cylinders will drain from the pan 18 into the rear chamber 17. Pan 18 also prevents oil in the chamber 16 from flowing over the wall 15 when the engine tips upwardly. A somewhat similar engine pan 19 covers substantially all of the rear chamber 17 but stops short of the transverse wall 15 so that oil draining from the rear four cylinders will flow into the rear chamber 17.

It is apparent that the oil draining from the engine is substantially all directed to the rear chamber 17, when the engine is level, rather than being divided between the two chambers formed in the sump 11.

An oil pump 21 (shown in section in Figure 3) is attached to the forward end of the crankcase and actually comprises two separate individual gear pumps designated as the upper pump 22 and the lower pump 23. A strainer 24 is located in the forward chamber 16 and a corresponding strainer 25 is located in the rear chamber 17. These strainers are of a conventional construction with a screen 26, and are supported on bosses 27 formed in the bottom of the crankcase. An intake pipe 28 leads from the rear strainer 25 through the transverse wall 15 (in which it is resiliently mounted) to the intake port 29 of the upper pump 22. Oil flowing therethrough is discharged through the discharge port 31 of this pump to a pipe 32 located exteriorly of the crankcase and reintroduced through an aperture 33 into the forward chamber 16 of the sump. It is readily seen that oil is normally drawn from the rear chamber 17 by the upper pump 22 and discharged into the forward chamber 16.

An intake pipe 34 leads from the front strainer 24 to the intake port 35 of the lower pump 23. The oil supplied by the intake pipe 34 passes through the lower pump 23 to the discharge port 36 of the lower pump and then through the bore 37 to an oil filter chamber 38 which includes a conventional filter element 39. The oil after passing through the filter element enters the vertical duct 41 which communicates with a similar duct in the engine block connecting with the various oil lines leading to the bearings and other mechanism to be lubricated. In the event that the oil filter should be clogged, a spring relief mechanism 42 is provided, including a spring weighted plunger 43 which opens a channel 44 leading directly from the oil filter chamber 38 to the vertical duct 41 referred to before. It will thus be seen that oil is withdrawn from the forward chamber 16 and pumped, after filtering, directly to the engine supply line.

A further connection is provided between the front and rear chambers through an overflow pipe 45 (best shown in Figures 4-6, inclusive), which is formed integrally with the crankcase. This overflow pipe has an opening 46 through the transverse wall 15 into the rear chamber 17; and opens into the forward chamber 16 through an L 47, having a horizontal opening 48 spaced a substantial distance above the floor of the crankcase. Thus any oil in the rear chamber 17, above the level of the top of the L 47 when the engine is level, will flow through the overflow pipe 45 to the forward chamber 16 until the levels in both chambers are equalized. As the engine is inclined upwardly, the natural tendency of the oil is to flow toward the rear of the engine; but the oil in the forward chamber 16 is prevented from taking such a course by the front pan 18 and cannot flow through the overflow pipe 45 after it reaches a minimum level for the particular degree of inclination defined by the elevation of the horizontal opening 48 in the L 47. However, when the engine is inclined downwardly, the oil from the rear chamber 17 is always free to flow through the overflow pipe 45 to the front chamber 16.

The operation of the device will be clarified through reference to Figures 7-9, inclusive. Figure 7 represents the engine operating on an even

keel in which the oil is withdrawn from the rear chamber 17 by the upper pump 22 and discharged into the front chamber 16 through the pipe 32. The oil in the front chamber is pumped through the lower pump 23 to the vertical duct 41 leading to the oil supply lines of the engine proper. Any excess oil in the forward chamber 16 not required for the engine, drains through the overflow pipe 45 to the rear chamber 17 and the process is repeated. When the engine is inclined downwardly, as shown in Figure 8, the oil tends to flow to the forward portion of the engine. Under these conditions, the rear strainer 25 may be entirely out of oil in the rear chamber 17, since any oil therein may flow through the overflow pipe 45 to the front chamber 16. Under these conditions, the upper pump 22 is inoperative but an adequate supply of oil is available in the forward chamber 16 and is pumped through the lower pump 23 directly to the engine lines. The oil draining from the engine is divided between the front and rear chambers as indicated by the arrows on the figure. In the event that the engine is inclined upwardly (as shown in Figure 9), the oil tends to move to the rear of the crankcase, and under ordinary conditions if the oil intake were located in the forward end, the oil lines would be starved. Under these conditions, however, all of the oil draining from the engine is directed to the rear chamber—although a portion may be trapped as at 49—but this can be drained into the rear chamber 17 through holes drilled in the engine pan 19. The oil in the rear chamber is pumped through the upper pump 22 and discharged into the front chamber. The level in the forward chamber is maintained due to the elevation of the opening 48 in the L 47 of the overflow pipe 45, while oil is withdrawn from the front chamber by the pump 23 and supplied to the engine.

From the diagrammatic showing, it will be apparent that regardless of the inclination of the engine, the pump will be supplied with an adequate amount of oil. This is attributable to the conjoint operation of the double pump and overflow pipe; and, at the same time, neither compartment of the crankcase can have an oversupply of oil.

In order to drain both chambers of the crankcase simultaneously, a drain plug 51 is provided which screws into the tapped boss 52 at the low point of the crankcase sump. The plug 51 has a shaft which extends into a cut-away cylinder 53 which has an aperture 54 opening to the front chamber 16 and an inside aperture 55 opening into the overflow pipe 45. The end of the plug 51 is piloted in a boss 56 on the overflow pipe 45. When the plug is screwed into position, it closes both apertures 54 and 55 in the cylinder 53 and prevents oil from the overflow pipe from entering the front chamber through it, or oil from either the overflow pipe or the front chamber draining out of the crankcase. Conversely, when the plug is removed, free passage is established between the overflow pipe and the front chamber, and the oil is free to flow out.

Both pumps 22 and 23 are driven by the single shaft 57 from the engine crankshaft or camshaft (the precise connection not being shown, as it does not form a part of this invention) and extends upwardly through the opening 58 in Figure 1. For purposes of clarity, the oil pump structure is not shown in Figures 1 or 2, but it will be quite clear from the sectional view in Figure 3. Directional arrows are used throughout to indi-

cate the flow of oil through the various chambers, pipes, and ducts referred to in the specification.

The operation of this device is believed to be apparent from the detailed description given. It is at once apparent that no matter what condition of operation is encountered within the limits of the tractive stability of the vehicle, the oil pump is assured of a steady and continuous supply of oil to be forced through the oil lines of the engine. This is obtained by the relatively simple construction shown, using a divided crankcase with a pair of co-operating pumps and an overflow device which is self-regulating. Under all conditions it maintains a supply of oil for the delivery pump whether the vehicle be inclined forwardly or rearwardly or is operating on a substantially even keel. The particular construction used is compact and requires no particular complexity of mechanism or connection. It presents no operating difficulty and is fully as dependable—so far as pump operation itself is concerned—as any of the conventional single pump arrangements, which are open, of course, to the further objection of failure when an insufficient supply of oil is forthcoming.

Some changes may be made in the arrangement, construction, and combination of the various parts of the improved device without departing from the spirit of the invention, and it is the intention to cover by the claims such changes as may be reasonably included within the scope thereof.

The invention claimed is:

1. In an engine crankcase, a transverse wall intermediate the ends of said crankcase, dividing said crankcase into a pair of chambers arranged successively longitudinally of said engine and having a substantially continuous floor, oil deflecting means between said engine and said chambers and normally directing the major part of the oil draining from said engine on said oil deflecting means to one of said chambers and forming at least a partial closure for the other chamber, a pump intake in said one chamber, a pump connected therewith effective to draw oil therefrom and deliver it to said other chamber, a pump intake in said other chamber, a second pump means effective to draw oil through said last-named pump intake and deliver it under pressure to said engine, a duct leading from the bottom of said one chamber and discharging into said other chamber at a point remote from said transverse wall substantially spaced above the bottom of said other chamber and above said oil intake in said other chamber, said duct effective to permit the free flow of oil directly to said other chamber from said one chamber when the engine is tilted in one direction of inclination and to retain a minimum quantity of oil in said other chamber when the engine is tilted in the opposite direction of inclination.

2. The structure of claim 1 which is further characterized in that a single drain plug is provided in said duct in said other chamber and co-operating as a closure with a passage in the wall of said duct between the interior of said duct and the interior of said other chamber and extending at least to the normal elevation of the bottom of said one chamber effective on removal to drain the oil from both said chambers therethrough.

3. In an engine crankcase, a transverse vertical wall intermediate the ends of said crankcase, dividing said crankcase into a pair of independ-

ent chambers arranged successively longitudinally of said engine, a pan means interposed between said chambers and said engine and normally effective to direct a major part of the oil draining from said engine into one of said chambers and forming at least a partial closure for the other said chamber along said wall, pump means mounted on said crankcase at one end thereof externally of said chambers and having a pair of gear pumps, a pipe leading from said one chamber to one said gear pump, a discharge pipe leading from said one gear pump to said other chamber, a pipe leading from said other chamber to said other gear pump, discharge means from said other gear pump communicating with the oil lines of said engine, an enclosed duct integrally formed with said crankcase and extending along the bottom of said other chamber substantially the entire length of said other chamber, said duct opening through said transverse wall at one end communicating with the said one chamber adjacent the bottom thereof, said duct opening to said other chamber at the other end of said duct, said opening being spaced a substantial distance above the bottom of said chamber.

4. The structure of claim 3, which is further characterized in that means is provided in said duct comprising an opening through the bottom of said crankcase, an opening between the interior of said duct and the interior of said other chamber, and a single plug externally insertable through said first opening to serve as a closure for both said openings and on removal to permit substantially complete drainage of oil from both said chambers through said first opening.

5. In an engine crankcase, a transverse vertical wall intermediate the ends of a crankcase dividing said crankcase into a pair of chambers, a drain pan arranged between the engine and one of said chambers normally effective to direct oil draining from said engine into the second of said chambers and preventing oil in said one chamber from flowing over said wall, pump means effective to pump oil from said second chamber and deliver it to first said chamber, a second pump means effective to pump oil from said first chamber and deliver it under pressure to said engine, and a duct communicating directly between said chambers, said duct opening into one chamber at a point substantially above the bottom thereof but permitting free flow of oil between said chambers to equalize the oil levels therein when said engine is substantially level and the oil level is above said last-mentioned duct opening.

6. In an engine crankcase, a transverse vertical wall intermediate the ends of crankcase dividing said crankcase into a pair of chambers, a drain pan arranged between the engine and one of said chambers normally effective to direct oil draining from said engine into the second of said chambers and preventing oil in said one chamber from flowing over said wall, pump means effective to pump oil from said second chamber and deliver it to first said chamber, a second pump means effective to pump oil from said first chamber and deliver it under pressure to said engine, and a duct passing through said transverse wall between said chambers, said duct opening into said second chamber at the bottom thereof and discharging into said first chamber at a point spaced a substantial distance from the bottom thereof.

7. In an engine crankcase, a transverse verti-

cal wall intermediate the ends of said crankcase dividing said crankcase into a pair of chambers, oil deflecting means between said engine and said chambers forming at least a partial closure for one of said chambers to prevent the oil therein from flowing over said wall, pump means effective to draw oil from the other said chamber and deliver it to said one chamber, a second pump means effective to draw oil from said one chamber and deliver it under pressure to said engine, a duct extending through the dividing wall for the free flow of oil between said chambers, said duct entering said other chamber adjacent the bottom thereof and discharging in said one chamber at a point substantially spaced from the bottom of said one chamber and remote from said dividing wall.
